United States Patent Office

Des. 221,931
Patented Sept. 21, 1971

221,931

CONTAINER CLOSURE

Ralph V. Bardell, deceased, late of Homewood, Ill., by Mary G. Bardell, executor, Homewood, Ill.

Filed Apr. 28, 1970, Ser. No. 22,694

Term of patent 14 years

Int. Cl. D9—02

U.S. Cl. D9—267

FIG. 1 is a top plan view of a container closure showing the new design;

FIG. 2 is a bottom view thereof;

FIG. 3 is a side elevational view thereof; and

FIG. 4 is a vertical sectional view taken through the center of the container closure.

What is claimed is:

The ornamental design for a container closure, as shown.
